Primary Examiner — Ania Aman*(74) Attorney, Agent, or Firm* — Brinks Gilson & Lione(57) **CLAIM**

We claim the ornamental design for an electric vehicle, as shown and described.

DESCRIPTION

FIG. 1 is a front perspective view showing an electric vehicle of the present invention;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front perspective view thereof showing doors being opened; and,

FIG. 10 is a front perspective view thereof showing an upper part of a body being separated from a lower part of the body. The broken lines show parts of the electric vehicle that represent unclaimed subject matter and form no part of the claimed design.

1 Claim, 10 Drawing Sheets(56)
